UNITED STATES PATENT OFFICE.

DAVID L. LINDQUIST, OF YONKERS, NEW YORK, ASSIGNOR TO OTIS ELEVATOR COMPANY, OF JERSEY CITY, NEW JERSEY, A CORPORATION OF NEW JERSEY.

REVERSAL-REGULATOR FOR SINGLE-PHASE MOTORS.

1,085,987.

Specification of Letters Patent.

Patented Feb. 3, 1914.

Application filed April 26, 1910. Serial No. 557,889.

To all whom it may concern:

Be it known that I, DAVID L. LINDQUIST, a subject of the King of Sweden, residing at Yonkers, in the county of Westchester 5 and State of New York, have invented a new and useful Improvement in Reversal-Regulators for Single-Phase Motors, of which the following is a specification.

My invention relates to a reversal regulator and it is described in connection with a single phase repulsion induction motor operating an elevator; although it may readily be adapted for other than elevator apparatus.

15 One of the objects of my invention is to prevent the motor from receiving current to impel it in a direction opposite to that in which it has been rotating unless the speed of the motor is within certain predetermined 20 limits.

Other objects will appear hereinafter.

In a single phase repulsion-induction motor, the reversal of the motor connections when the motor is running as an induction 25 motor will not affect the direction of rotation of the motor, or effect a reversal of the motor.

My reversal regulator consists of a contact arrangement operative in conjunction with 30 the short-circuiting device of the motor which changes it from a repulsion to an induction motor.

Referring now to the accompanying drawing, the motor M is operative to raise 35 and lower the elevator car C and its counter-weight W by means of the traction drum E. The brake B is operative in the well known manner. In connection with the traction drum are found machine limit switches 40 comprising a cam 21 mounted upon a shaft 22 and operative to engage either of the up or down limit switch levers U or D, at the corresponding limit of travel of the elevator car.

45 A car controller K is located in the elevator car C, and the supplying of current to the motor M is effected by means of the reversing switches R and R' and the switch P. The main switch S connects the entire system to the outside mains.

The contact clips 1 and 2 are secured to the housing of the motor M; the contact

ring 3 carried by the centrifugal governor 4 is insulated from its support and is adapted to make connection between the contact 55 clips 1 and 2 when the said ring is in a certain position. The centrifugal device 4 which changes the motor from a repulsion to an induction motor by means of a short-circuiting device, also connects the contact 60 ring 3 to the motor armature and by its action automatically opens and closes the connection made by the contact ring 3 with the contact clips 1 and 2 in accordance with the speed of the rotating part of the motor, thus 65 making or breaking the circuit through the contact clips 1 and 2 and the contact ring 3.

The magnet windings of the reversing switches R and R' are connected through the limit switches D and U and to the contacts 70 of the car controller switch K, so that when the hand lever 5 of the controller switch is moved to the right or left, the corresponding magnet winding is energized. The magnet winding of the operating switch P 75 is also connected to the contacts of the car switch K but is dependent for initial energization upon the position of the contact ring 3. This operating switch P also has contacts 6 and 7 whose function is to maintain 80 a circuit through the operating switch magnet winding after the said circuit has been initially closed. The opening of either limit switch breaks the circuit through the corresponding reversing switch. 85

It is not thought necessary to follow in detail the circuits through the reversing switches to the motor, it being sufficiently clear to state that the motor is presumed, in the present embodiment, to be of a single 90 phase type and it being understood that the source of current is from the motor contact 8 through the windings of the motor to the contact 9 and from the contact 10 through the motor windings to the contact 11. 95

In order that the operation of my invention may be more readily understood, I shall describe the operation of the same in connection with the present embodiment.

If it is desired to start the motor, the 100 hand lever 5 of the car switch K is thrown either to the right or to the left of the central position. Let us say it is thrown in the direction to close the reversing switch R

and subsequently the operating switch P. As soon as contact is made with the car switch contact 13 a circuit is closed from the main 14 through this car switch contact 13, thence through the conductor 15, magnet winding 16, conductor 17, contact clip 1, contact ring 3, contact clip 2, conductor 18, contact 6, conductor 19 to the other main 20. This causes the magnet winding 16 of the operating switch P to be energized, the switch closed, and the auxiliary contacts 6 and 7 to be connected. The connection of these contacts 6 and 7 causes a holding circuit to be closed through the magnet winding of the operating switch. This circuit is traced from conductor 17, through the contacts 7 and 6, conductor 19 and the main 20 instead of through the contact ring 3. The motor then receives starting current to impel it in a given direction as a repulsion motor and as soon as it attains a predetermined speed of rotation, the centrifugal device which operates the short-circuiting device and governs the action of the contact ring 3, automatically places this contact ring out of engagement with the fixed contact clips 1 and 2, thereby breaking the circuit from conductor 17 to conductor 18; but at this time the operating switch P has been closed and the contacts 6 and 7 maintain a circuit through the magnet winding of the operating switch. Now, if the car operator returns the hand lever 5 to its central position the operating switch P and the reversing switch R become deenergized and the motor is stopped in the ordinary manner. But if, instead of stopping the hand lever at the central position, the car operator swings it past the central position to operate the motor in the opposite direction, a circuit will not be closed to the motor in the reverse direction until the speed of the motor is dropped to a certain predetermined limit. This is evident from the position of the contact ring 3 since it will not make connection between the clips 1 and 2 until the centrifugal device 4 has allowed it to return to its unoperated position, thus preventing an initial circuit from being closed through the magnet winding of the operating switch. The effect of this is that the connections of the motor can not be reversed while the motor is running as an induction motor. If the connections could be so reversed, the direction of rotation of the motor would remain unchanged, since it is a single phase motor. With my arrangement, however, the movement of the hand lever 5 to either running position effects the rotation of the motor only in the intended direction; for if it is running as an induction motor it cannot be energized to reverse its direction of rotation until it slows down sufficiently to close the centrifugal short-circuiting device, thereby again becoming a

repulsion motor, from which condition it may then be started in either direction. The limit switches D and U are inserted in series with the windings of the reversing switches R and R' and are operative to open the circuits thereof when the said limit switches are automatically opened. 70

In elevator apparatus it is very frequently desired to reverse the direction of rotation of the motor at very short intervals of time, say for instance, in bringing the elevator car to a stop at any floor and the car operator will throw the car switch hand lever from one position to the other in an effort to make a good landing. This practice is very injurious not only to the motor but also to the elevator apparatus and the controlling means. My invention prevents this rapid reversal by preventing the closure of the operating switch until such a time as the speed of the motor has fallen to a predetermined safe limit when the motor may be reversed with safety and without any injurious effects upon the elevator apparatus. This device is also automatic in operation and does not depend upon the knowledge or discretion of the car operator. 80

I desire not to be limited to the specific construction herein described, for it is evident that those skilled in the art may make various changes without departing from the spirit or scope of the invention and may employ it in connections other than with elevator apparatus. 95

What I claim and desire to secure by Letters Patent of the United States, is:— 100

1. The combination of an electric motor, a circuit comprising a switch through which current is supplied to the motor, reversing switch mechanism, and a speed governor to prevent the closure of said switch after the reversing switch mechanism has operated during the running of the motor, until the speed of the motor has been reduced. 105

2. The combination of an electric motor, reversing switches, a switch in the motor circuit in series with said reversing switches, and means mechanically operated by the motor to prevent the closure of said switch while the motor is operating above a predetermined speed. 110

3. The combination of an electric motor, an electromagnetic switch in a supply circuit for the motor, means to effect the closing of said switch, while the motor is operating below a predetermined speed, and means to prevent the energization of the switch magnet from said switch closing means while the switch is in open position and the motor rotating above a predetermined speed. 120

4. The combination of an electric motor, reversing switches therefor, an electromagnetic switch in circuit with the reversing switches and having the circuit of its mag- 130

- net winding controlled by the said switch, and means controlled by the speed of the motor for maintaining a circuit for the said magnet winding independently of the said switch. 5
5. The combination of an electric motor, an electromagnetic switch in the supply circuit for the motor, means operated by said switch for opening the circuit of the switch magnet when the switch has opened, and means controlled by the speed of the motor for maintaining said magnet circuit independently of the said switch while the speed of the motor is below a predetermined 10 value. 15
6. The combination of an electric motor, a circuit connecting the motor to a source of current supply, an electromagnetic switch in said circuit, switch contacts carried by said switch and separated when the switch is open, said contacts being in the circuit of the switch magnet, a shunt circuit connected across said contacts, and means controlled by the speed of the motor for opening said 20 shunt circuit. 25
7. In an elevator, the combination of an electric motor, reversing switches, an electromagnetic switch in circuit with said reversing switches and the motor, contacts carried by said electromagnetic switch and in circuit with the magnet winding of the switch, a shunt circuit across said contacts, and means operated by the motor for automatically maintaining the said shunt circuit 30 open while the speed of the motor is above a predetermined value. 35
8. In elevator apparatus, the combination of a motor, an electro-responsive operating switch, circuit closing means joined to the motor, centrifugal means connected to the motor to automatically operate the circuit closing means, and auxiliary contacts in connection with the operating switch to maintain a closed circuit through the operating 40 switch magnet winding. 45
9. In elevator apparatus, the combination of a motor, circuit closing means joined to the motor, an electro-responsive operating switch, a manual switch for initially energizing and for deenergizing the operating switch, and centrifugal means joined to the motor to prevent the reenergization of the operating switch after the motor has been started until the speed thereof falls to a 50 certain limit. 55
10. In elevator apparatus, the combination of an alternating current motor, an electro-responsive operating switch, contacts in connection with the motor to close a circuit through the magnet winding of the operating switch, means in connection with the operating switch to maintain an energizing circuit through the said winding when the switch is closed, and means dependent upon the speed of the motor to pre- 60 65
- vent the magnet circuit from being closed when the speed of the motor exceeds a prescribed limit. 70
11. In elevator apparatus, the combination of a motor, contacts fixed to the motor housing, a contact ring to connect the said contacts, a centrifugal device joining the contact ring to a rotating part of the motor, reversing switches for the motor, an electromagnetic operating switch having auxiliary contacts for maintaining a circuit through the operating switch magnet winding while the switch is closed, and a car switch for initially closing and for opening energizing 75 circuits through the reversing switches and 80 the operating switch. 85
12. In elevator apparatus, the combination of an alternating current motor, reversing switches therefor, an electro-responsive operating switch, a contact device automatically opened and closed by the motor, a car switch, connections to close an energizing circuit for the operating switch through the contact device, and auxiliary contacts joined by the closure of the operating switch to 90 maintain a holding circuit for the operating switch magnet winding after the circuit through the said contact device is broken. 95
13. In elevator apparatus, the combination of a single-phase repulsion-induction motor having a centrifugal short-circuiting device, a contact device operated by the centrifugal device, reversing switches for the motor, and means in connection with the switches and the contact device for preventing the said motor circuits from being reversed until the speed of the motor is reduced. 100
14. In elevator apparatus, the combination of a single-phase repulsion-induction motor having a centrifugal short-circuiting device for automatically changing the motor from a repulsion to an induction motor, a contact device operated by and simultaneously with the short-circuiting device, and means in connection with the said contact device to prevent the reversal of the motor. 105
15. In an elevator apparatus, the combination of a single-phase repulsion-induction motor having a centrifugal short-circuiting device mounted on the motor to change it from a repulsion to an induction motor when the motor speeds up, an elevator car switch, reversing switches for the motor controlled from the car switch, an operating switch, a contacting device operated by the centrifugal short-circuiting device and operating simultaneously with the said operating switch to prevent the energization of the motor in a reverse direction to which it is 110 operating until the speed of the motor has been reduced. 120
16. In elevator apparatus, the combination of a single-phase repulsion-induction motor having a centrifugal short-circuiting 125 130

device, a contact device operated by the centrifugal device, reversing switches for the motor, an elevator car switch for energizing the reversing switches, an operating switch, means in connection with the operating switch and the said contact device to prevent the reversal of the motor from the car switch until the motor has been stopped, and a limit switch in series with each reversing switch

magnet winding to open the corresponding reversing switch.

In testimony whereof, I have signed my name to this specification in the presence of two subscribing witnesses.

DAVID L. LINDQUIST.
